DESK

Filed Oct. 6, 1922

UNITED STATES PATENT OFFICE.

ALEXANDER S. FALLS, OF CHICAGO, ILLINOIS.

DESK.

Application filed October 6, 1922. Serial No. 592,686.

To all whom it may concern:

Be it known that I, ALEXANDER S. FALLS, a citizen of the United States, and a resident of the village of Glencoe, in the county of Cook and State of Illinois, have invented certain new and useful Improvements in a Desk; and I do hereby declare that the following is a full, clear, and exact description of the same, reference being had to the accompanying drawings, and to the numerals of reference marked thereon, which form a part of this specification.

It has become common practice in the use of bookkeeping machines, billing machines, and other typewriting machines, to have the paper upon which the machine works, come in a long, continuous roll, or in the form of a continuous web folded zig-zag into a package. In desks for typewriter machines heretofore designed, no convenient place has been found for such a supply of paper. It has either been supported upon a bracket forming part of the bookkeeping machine or mounted upon an independent support.

It is an object of the present invention to provide a receptacle for holding such a supply of paper which can be easily and quickly positioned in the proper relation to the typewriting machine.

It is a further object of this invention to so mount the receptacle in the desk that when the machine is not in use, the receptacle may be moved to the interior of the desk and so give a compact arrangement.

It is a further object of the present invention to provide an arrangement wherein the ordinary drawers of the desk when closed and locked shall prevent the movement of the receptacle containing the supply of paper for the bookkeeping machine.

Other and further important objects of the invention will be apparent from the disclosures in the accompanying drawings and the following specification.

The invention (in a preferred form) is illustrated in the drawings and hereinafter more fully described.

On the drawings:

Figure 1 is a front view of the desk.

Figure 2 is an end view looking at the desk from the left and showing a portion thereof in section upon the line 2—2 of Figure 1.

Figure 3 is a section upon the line 3—3 of Figure 1.

Figure 4 is an enlarged detail section upon the line 4—4 of Figure 3.

Figure 5 is a section upon the line 5—5 of Figure 4.

Figure 6 is a broken detail view showing a modified form of pivotal mounting.

As shown on the drawings:

The desk is of the form usually employed as a typewriter desk having a space 10 for the knees of the person operating the book-keeping, billing or other typewriting machine. It is provided with legs 12 at each left-hand corner and at the right-hand side of the space 10. At the right of the space 10 are mounted a set of drawers 13 in the usual way, except that these drawers do not go back into the desk as far as is usual in the prior art.

In the space behind the drawers 13 and behind the space 10 are mounted drawers 75 or receptacles 14 preferably of the same depth as the drawers 13 so that a common horizontal partition or shelf 15 can be used to separate the two receptacles 14 and also the two drawers 13. The back of the desk 80 16 is open for a part of its extent at one end, as shown at 17, to afford a space through which the receptacles 14 may swing and emerge. In order to provide for the motion of the receptacles 14, they are 85 connected to the back 16 by hinges 18 adjacent the right-hand edge of the space 17. One leaf of each hinge is secured to the back of the desk as shown at 20 in Figure 5. The other leaf is secured to the vertical 90 wall of the receptacle 14 which, in the position in which this receptacle is within the desk, is the rear wall, as illustrated in full lines in Figure 3. When the receptacle is moved by turning about these hinges, the 95 rear wall becomes a side wall, and the end which was the right-hand end of the receptacle becomes the rear end, as may be seen by noticing the dotted line position in Figure 3. A handle 22 is attached to each receptacle 14 in the middle of the space 17 for convenience in moving the receptacle to 100 open position.

The desk is provided with its usual solid top 23 for the reception of the bookkeeping machine and for the ordinary desk work. If desired, there may also be provided a sliding shelf 24 above the drawers 13 as is usual in desk constructions. The drawers 13 are provided with handles 27 and locks 110

25 which may be made to lock the several drawers individually or may be made to lock all the drawers by the operation of one of the locks, as is well understood in the art.

5 It will be observed from the showing in Figure 3 that, when the drawer 13 is closed and the receptacle 14 is in the full line position, the receptacle 14 cannot be moved to the dotted line position. If, therefore, the 10 drawer 13 is locked, the receptacle 14 is secured in closed position. On the other hand, when the drawer 13 is open, the receptacle 14 may be moved to the dotted line position. The drawer 13 may then again be 15 closed and will serve to prevent the return of the receptacle 14 to its closed position. Thus, when the drawer 13 is locked, the receptacle 14 is retained in whichever position it was in at the time the drawer 13 was 20 closed.

In the form just illustrated, I have shown two receptacles 14, one above the other. Obviously, the desk may be built with but one receptacle 14 if desired, and if so built, the 25 drawer 13 which is opposite the portion of the desk not occupied by a receptacle 14 may be made of the usual length, extending merely to the back 16 of the desk.

The modification shown in Fig. 6 has 30 pivot pins 30 instead of hinges. These pins are secured to the top and bottom of the side wall of the drawer 14 in any desired way; for example, by being integral with plates 31 fastened to the edges of the wall 35 by screws. The pivot pins are received in sockets in the body of the desk. Preferably these sockets are lined with metal thimbles as shown at 32 to insure good durability.

In the use of this desk, the scrolls or folds 40 of paper for typing purposes are kept in the receptacles 14. From the upper receptacle 14 the paper may be led into the typing machine when said receptacle has been 45 swung into dotted line position as shown in Figure 3. The lower receptacle 14 may be used for retaining or storing an extra supply of such paper.

I am aware that numerous details of construction may be varied through a wide 50 range without departing from the principles of this invention, and I therefore do not purpose limiting the patent granted otherwise than necessitated by the prior art.

I claim as my invention:

1. In a typewriter desk, a desk top adapted 55 to support a typewriter and having a space beneath the front part thereof for the operator's knees, drawers mounted beneath said top at one side of said knee space, and a receptacle for paper supported at the rear 60 of said drawers and of said knee space and rotatable beyond the desk back in alignment with said knee space.

2. In a typewriter desk, a desk top adapted 65 to support a typewriter and having a space beneath the front part thereof for the operator's knees, drawers mounted beneath said top at one side of said knee space, a back panel having an opening in alignment with said knee space, and a receptacle for 70 paper normally disposed within the desk but rotatable through said opening into alignment with said knee space.

3. In a typewriter desk, a desk top adapted 75 to support a typewriter and having a space beneath the front part thereof for the operator's knees, drawers mounted beneath said top at one side of said knee space, a back panel having an opening in alignment with said knee space, and a receptacle for 80 paper normally disposed within the desk but rotatable in a horizontal plane through said opening into alignment with said knee space.

4. In a desk, a receptacle pivoted within 85 the desk and rotatable rearwardly thereof, and a drawer adapted when closed to lock said receptacle against rotating movement.

5. In a desk, a receptacle pivotally mounted 90 therein, a drawer movable into and out of the path of movement of said receptacle, and means for locking said drawer in said path.

6. In a desk, a receptacle pivotally mounted 95 therein, and a drawer movable into and out of the path of movement of said receptacle, the drawer being in said path when closed.

In testimony whereof I have hereunto 100 subscribed my name in the presence of two subscribing witnesses.

ALEXANDER S. FALLS.
